Des. 207,077
Patented Feb. 28, 1967

207,077

COMBINATION RANGE TOP AND SINK OR THE LIKE

Mike Tecton, Washington, D.C.
(356 N. Kensington, Arlington, Va. 22207)

Filed Oct. 24, 1965, Ser. No. 87,915

Term of patent 14 years

(Cl. D81—25)

FIG. 1

FIG. 2

FIG. 1 is an isometric view of a combination range top and sink or the like, showing my new design;

FIG. 2 is a top plan view thereof.

I claim:

The ornamental design for a combination range top and sink or the like, substantially as shown.
